SPEED MICROMETER

Peter J. Jackman, New York, N. Y.

Application September 13, 1944, Serial No. 553,881

6 Claims. (Cl. 33—164)

1

This invention relates to a micrometer.

It is particularly aimed to provide a construction which will speed up and facilitate the operation and ease of manipulation of a micrometer by bringing the measuring surfaces together or by separating them to any extent within the scope of operation.

It is further aimed to provide a novel structure in which there will be less pressure on the measuring surfaces, especially so that a safety frictional ratchet or stop can be eliminated or dispensed with.

It is further aimed to generally improve the construction of a micrometer, and provide one which is facile to assemble and disassemble as well as relatively inexpensive to manufacture.

The more specific objects and advantages will become apparent from the description following taken in connection with accompanying drawings illustrating an operative embodiment.

In said drawings—

Figure 1 is a side elevation of a speed micrometer constructed in accordance with the invention;

Figure 2 is a view on an enlarged scale, being taken substantially centrally through the device, with the major portion of the frame broken away;

Figure 3 is a cross section taken on the line 3—3 of Figure 2;

Figure 4 is a cross section taken on the line 4—4 of Figure 2;

Figure 5 is a detail of the central parts of Figure 1, with more of the parts shown in section to disclose details;

Figure 6 is a cross section taken on the line 6—6 of Figure 5;

Figure 7 is a fragmentary plan view of the parts adjacent the actuator; and

Figure 8 is a cross section taken on the line 8—8 of Figure 7.

Referring specifically to the drawings wherein like reference characters designate like or similar parts, 10 indicates a conventional frame, usually of U-shape and provided with an interior anvil as at 11. From the frame, a tubular barrel 12 rigidly projects.

A spindle 13 is disposed concentrically of the barrel 12, having a reduced portion 14 journaled in a portion of the frame 10 as shown, and projecting into the space of the frame in alignment with the anvil 11 for coaction with the latter in measuring. The spindle 13 at one portion thereof, has longitudinally disposed gear teeth 14a and adjacent its outer end has left-hand screw threads 15. Such screw threads 15 are enmeshed

2

with the screw threads of a nut 16 located within the outer end of the barrel 12 and rigidly fixed thereto. Outwardly of the nut 16, spindle 13 has a portion 17 rigidly connected with an external cap or sleeve 18. The spindle 13 and sleeve 18 may be integral if desired.

An actuating device in the form of a sleeve or tumbler 19 is journaled on the exterior of the barrel 12 and has one end in abutment against the frame 10. Such actuating device has an enlargement 20 provided thereon in any suitable manner. To this end, sleeve or actuating device 19 has an outwardly extending flange at 21 peripherally terminating in an inwardly extending flange 22 which is in screw-threaded engagement with an annular wall 23 of a housing 24. Such housing 24 is journaled on an outwardly extending wall 25 of a collar 26 surrounding and rigidly secured on the barrel 12.

Barrel 12 has an opening 28 closed by and beneath which a seat member 27 is welded or otherwise rigidly fixed on the barrel 12 for positioning of such portion. A relatively fixed pin 30 at one end extends into the opening 28 resting on seat member 27 and has a flat portion at 31 so that a set screw 32 which is screw threaded in an opening or socket in the collar 26 may extend into opening 28 be tightened against portion 31 to hold pin 30 rigidly but removably in place and also to hold collar 26 against rotation relative to barrel 12. A set screw 33 may be threaded into openings in the wall 24 and flanges 22 to prevent loosening of housing 20 with respect to the actuating device 19.

It will be noted that the pin 30 extends internally of the housing and substantially throughout its length, parallel to the spindle 13. A bushing or bearing 35 is rigidly fixed on the barrel 12, to receive one end of pin 30 and it is relatively close to the flange 21 whereby the actuating device will be held against longitudinal displacement by and between the same and frame 10. In addition washers 36 are strung on the pin 30 and between the washers, a gear or pinion 37 is journaled on such pin 30 at 38. The teeth of the gear or pinion 38 are enmeshed with the teeth 14a of the spindle and also with teeth of an internal rack 39 formed on the wall 24 of the housing 20.

It will be noted that conventional or other suitable calibrations may be provided longitudinally on the exterior of the barrel 12 as at 40 and that suitable calibrations at 41 may also be provided on the cap or thimble 18, about its inner edge portion.

As a result of the construction described, either the housing 20 or remainder of the actuating device 19 may be manually engaged and turned in order to cause the teeth 39 to actuate the gear 31, which in turn through teeth 14 actuate the spindle 13. This actuation causes the spindle 13 to slide in either direction due to the coaction of the screw threads 15 with those within the nut 16. As the screw threads 15 are left-handed, the cap or thimble 18 and the spindle 13 will close when the actuating device 19 is turned to the right as in the manner of the conventional micrometer.

Various changes may be resorted to provided they fall within the spirit and scope of the invention.

I claim as my invention:

1. A micrometer of the class described having a frame, a barrel extending therefrom, a spindle journaled in the frame and disposed within the barrel, said barrel and spindle having interengaging threaded portions, an actuating device journaled on the barrel and including an internal gear, said spindle having a toothed part forming a gear, and gearing between the actuating device and the spindle and enmeshed with the internal gear and spindle gear.

2. A micrometer of the class described having a frame, a barrel extending therefrom, a spindle journaled in the frame and disposed within the barrel, said spindle having a gear, an actuating device journaled on the barrel and including a gear, gearing between the actuating device and the spindle and meshing with the gears thereof, a thimble on the barrel, and a screw thread connection between the spindle and barrel, said actuating device having an enlargement housing the gearing thereof.

3. A micrometer of the class described having a frame, a barrel projecting therefrom, a spindle journaled in the frame and extended through the barrel, an actuating device journaled on the barrel, said device having an enlargement, a gear, means mounting the gear on the barrel within the enlargement, internal teeth on the enlargement engaged by the gear, teeth on the spindle

engaged by the gear, a thimble attached to the spindle surrounding one end of the barrel, and a screw connection between the spindle and barrel.

4. A micrometer of the class described having a frame, a barrel projecting therfrom, a spindle journaled in the frame and extended through the barrel, an actuating device journaled on the barrel, said device having an enlargement, a gear, means mounting the gear on the barrel within the enlargement, internal teeth on the enlargement engaged by the gear, teeth on the spindle engaged by the gear, a thimble attached to the spindle surrounding one end of the barrel, a screw connection between the spindle and barrel, said screw connection being left hand.

5. A micrometer of the class described having a frame, a barrel projecting therefrom, a spindle journaled in the frame and extending into the barrel, an actuating device journaled on the barrel, said device having an enlargement, a gear, means mounting the gear on the barrel within the enlargement, internal teeth on the enlargement engaged by the gear, teeth on the spindle engaged by the gear, a thimble attached to the spindle and surrounding one end of the barrel, said gear mounting means including a pin on the barrel extending into the enlargement, said gear being journaled on said pin, and an element on the barrel mounting one end of the pin and serving as a stop to restrict longitudinal movement of the actuating device relatively to the barrel.

6. In a micrometer, a frame, a barrel projecting therefrom, a spindle extending through the barrel and in threaded engagement therewith, one end of the spindle being journaled in and extending through a part of the frame, said spindle having a gear portion, an actuator journaled on the barrel and provided with an annular housing, a shaft extending through the housing, a pinion mounted on the shaft and meshed with the spindle gear portion, and an internal rack on said housing meshing with the pinion for rotating the spindle when the actuator is revolved.

PETER J. JACKMAN.
